CLAIM

The ornamental design for a face for a lighting softbox as shown and described.

DESCRIPTION

FIG. 1 is a front perspective view of a face for a lighting softbox, in accordance with a first embodiment of the present invention;

FIG. 2 is a front perspective view of the face for a lighting softbox of FIG. 1;

FIG. 3 is a front elevation view of the face for a lighting softbox of FIG. 1;

FIG. 4 is rear elevation view of the face for a lighting softbox of FIG. 1;

FIG. 5 is a left elevation view of the face for a lighting softbox of FIG. 1;

FIG. 6 is a right elevation view of the face for a lighting softbox of FIG. 1;

FIG. 7 is a top plan view of the face for a lighting softbox of FIG. 1;

FIG. 8 is a bottom plan view of the face for a lighting softbox of FIG. 1;

FIG. 9 is a front perspective view of a face for a lighting softbox, in accordance with a second embodiment of the present invention;

FIG. 10 is a front elevation view of the face for a lighting softbox of FIG. 9;

FIG. 11 is rear elevation view of the face for a lighting softbox of FIG. 9;

FIG. 12 is a left elevation view of the face for a lighting softbox of FIG. 9;

FIG. 13 is a right elevation view of the face for a lighting softbox of FIG. 9;

FIG. 14 is a top plan view of the face for a lighting softbox of FIG. 9; and,

FIG. 15 is a bottom plan view of the face for a lighting softbox of FIG. 9.

(Continued)

The broken lines shown in FIGS. 1-15 form no part of the claimed design. The additional broken lines shown in FIG. 1 depict environment and form no part of the claimed design.
